UNITED STATES PATENT OFFICE.

AUGUST DOERING, OF BURT, IOWA, ASSIGNOR OF THREE-FOURTHS
TO WM. K. FERGUSON, E. J. MURTAGH, AND WILFRID P. JONES,
OF ALGONA, IOWA.

PLATFORM-SCALE.

SPECIFICATION forming part of Letters Patent No. 693,847, dated February 25, 1902.

Application filed March 23, 1901. Serial No. 52,559. (No model.)

To all whom it may concern:

Be it known that I, AUGUST DOERING, a citizen of the United States, residing at Burt, in the county of Kossuth and State of Iowa, have 5 invented certain new and useful Improvements in Platform-Scales; and I do hereby declare the following to be a full, clear, and exact description of the invention, such as will enable others skilled in the art to which 10 it appertains to make and use the same.

This invention relates to scales for weighing wagons, cars, and rolling-stock of every description, the purpose being accuracy, responsive and coöperative movement between 15 the parts, durability, and simplicity of construction. The mountings are such as to reduce the engaging surfaces to the smallest amount possible and prevent slipping or displacement, thereby obviating delays incident 20 to readjustment and fitting of the parts when they become disarranged.

For a full description of the invention and the merits thereof and also to acquire a knowledge of the details of construction of the means 25 for effecting the result reference is to be had to the following description and drawings hereto attached.

While the essential and characteristic features of the invention are necessarily susceptible 30 of modification, still the preferred embodiment of the invention is illustrated in the accompanying drawings, in which—

Figure 1 is a plan view of a platform-scale embodying the invention, parts being broken 35 away. Fig. 2 is an end view. Fig. 3 is a detail view in perspective of the mounting for an arm of a lever. Fig. 4 is a perspective view of the inner ends of a pair of levers, showing the connecting means. Fig. 5 is a detail 40 view of the connection between the scale-beam and the arm of the rock shaft or bar connected with the platform-levers. Fig. 6 is a detail view in perspective of the rock-shaft or connecting-bar between the scale-beam and 45 platform-levers. Fig. 7 is a transverse section of the platform and longitudinal sills. Fig. 8 is a detail section, on an enlarged scale, showing the antifriction-bearing between the opposing sides of adjacent beams of the plat-

form and well. Fig. 9 is a plan view of the 50 levers and connections arranged for weighing cars and long bodies.

Corresponding and like parts are referred to in the following description and indicated in all the views of the drawings by the same 55 reference characters.

As is usual in devices of this character, in the well or pit, in which are located the platform-levers, mountings, and connections therefor, a frame is provided and surrounds 60 the upper end of the said pit, and in the present instance this frame consists of longitudinal sills 1 and cross-timbers 2, rigidly connected at their ends with the sills 1, so as to form a substantial structure.

The platform comprises a series of longitudinal timbers 3 and planks or boards 4, nailed or otherwise secured to the substructure comprising the timbers 3. The platform-levers 5 are of ordinary construction 65 and comprise divergent arms, which have pivotal connection with the platform and frame of the pit or well at their outer ends, their inner ends being connected to a rock-shaft 6 in such a manner as to effect a turning there- 70 of when a weight is imposed upon the platform, so as to cause a movement of the scale-beam 7, whereby the weight of the load may be determined in the usual way. Inasmuch as each arm of the platform-levers is simi- 75 larly mounted, a detailed description of one only will be given. An upright or pillow-block 8 is bolted or otherwise fastened to the frame of the pit or well, and its upper end is cut away or forked to provide spaced mem- 80 bers or branches to receive between them the outer end of an arm of a lever 5. The upper ends of the branches are widened and de- 85 pressed to receive a fulcrum-bar 9 of approxi- 90 mately triangular form in cross-section, an edge of said fulcrum-bar obtaining a bearing upon the upright or pillow-block 8. An opening 10 is formed near the outer end of 95 each arm of the levers and receives a pin 11, from which a link 12 is pendent, and which receives a rod or bar 13, having a knife-edged bearing 13^a to engage said link, and by means of which corresponding arms of the respec-

tive levers are connected, said rods or bars 13 being attached to the platform in any substantial and rigid manner. The inner ends of the levers 5 may be connected in any manner which will admit of their free movement without binding, and, as shown, the inner end portions overlap or pass by each other and are connected by a shackle in a manner presently to be described.

10 The scale-beam 7 may be of any type and graduated and constructed in any desired way and is mounted in a box or casing 15, conveniently located.

15 The rock-shaft or connecting rod or bar 6 is mounted so as to turn freely and is pro-

vided near one end with an arm 16 and near its opposite end with an arm or lever 17 of greater length. This part 6 may be a length of pipe or tube or may be solid, and its out-

20 line in cross-section may be of any desired form, these details being immaterial so long as the part serves to transmit motion from the

platform-levers to the rod attached to the scale-

beam. Knife-edged bearings 18 are provided

25 upon the under side of the rock-shaft 6 at suitable points and are mounted upon stand-

ards 19, secured to a sill or timber located

in the pit or well. The connecting-bar 20 is adapted to be lengthened and shortened,

30 being composed of parts connected by a turn-

buckle, and this connecting-bar is hooked at

its upper end in the usual way to make de-

achable connection with a yoke 21, having

loose connection with the scale-beam. A

35 yoke 22 is fitted to the lower end of the bar 20, and the plate 23 thereof is recessed or de-

pressed in its top side to receive a fulcrum-

stud 24, pendent from the outer end of the

lever or arm 17. The short arm or lever 16

40 is provided at its free end with a pin 26 of

approximately triangular form in cross-sec-

tion, and eyebolts 27 are pendent from oppo-

site ends thereof and are connected by plates

28 and 29, which are recessed in their top

45 sides to receive fulcrum-studs 30, pendent

from the inner ends of the platform-levers.

This construction is shown most clearly in

Fig. 4. The plates 28 and 29 are vertically

adjustable, being supported by nuts 31, fitted

50 to the threaded portions of the eyebolts 27.

This manner of connecting the platform-levers

to the arm 16 admits of independent ad-

justment of the said levers with reference to

the arm 16, whereby variation in wear, work-

55 manship, or assembling of the parts may be

compensated.

As is well known, the platform and scales

of the character aforesaid have a limited ver-

tical and longitudinal play, the vertical move-

60 ment being necessary to admit of the load

depressing the platform and the longitudi-

nal play resulting from the loose connection

between the platform and its supporting-le-

vers. It is the aim to have adjacent beams of

the platform and pit-frame come as close to-

gether as possible, so as to prevent dangerous

play or movement of the platform, and as a result the beams contact and detract mate-
rially from the accuracy of the scales. The
frictional engagement between these beams 70
is reduced to a minimum amount in accord-
ance with this invention by interposing anti-
friction-bearings between them. Hence plates
32 and 33 are attached to the opposing faces
or sides of the adjacent beams, and one of the 75
plates is formed with a race or seat 34 to re-
ceive balls 35, the latter engaging with the
opposite plate. This construction is shown
most clearly in Fig. 8 and admits of the plat-
form moving freely, vertically, and longitudi- 80
nally.

When the scales are constructed for weigh-
ing railroad-cars or long bodies or objects, it
is preferred to separate the platform-levers 5
and to provide a rock shaft or bar 6 for each 85
and to extend the arms or levers 17 and con-
nect them with the bar 20 in a manner simi-
lar to connecting the inner ends of the levers
5 with the lever 16, as shown in Fig. 4. The
arms 16 at the inner ends of the rock-shaft 6 90
are connected with the inner ends of the le-
vers 5 in a manner similar to connecting the
levers 17 with the rod 20, as indicated in Fig.
5. It is to be understood that the loose con-
nections between the levers 5 and arms or le- 95
vers of the rock-shaft 6 may be provided in
any way so long as free movement is had with-
out binding of the parts.

Having thus described the invention, what
is claimed as new is—

1. In platform-scales, levers having their
inner ends overlapped and provided with
pendent pivot-studs, a rock-shaft connected
to the platform-levers and having an arm or
lever, a shackle connected to said arm or le- 105
ver and comprising upper and lower plates
recessed in their top sides to receive the
pendent pivot-studs of the platform-levers,
and means for independently adjusting the
said plates, substantially as described. 110

2. In platform-scales, levers having their
inner ends overlapped and provided with
pendent pivot-studs, a rock-shaft connected
to the platform-levers and having an arm or
lever carrying a bearing-pin, eyebolts pend- 115
ent from said bearing-pin, upper and lower
plates mounted on the eyebolts and recessed
in their top sides to receive the pendent pivot-
studs of the platform-levers, and nuts on the
eyebolts for independently adjusting the said 120
plates, substantially as described.

3. In platform-scales, platform-levers, a
rock-shaft provided with two laterally-pro-
jecting arms, a shackle pivotally and adjust-
ably connecting one of said arms to the plat- 125
form-levers, a scale-beam, a longitudinally-
adjustable bar connected with the scale-
beam, a yoke carried by said bar, a plate ad-
justably connected to the yoke, and having a
recess in its top, and a pendent pivot-stud on 130
the other arm of the rock-shaft and fitting in
said recess, substantially as described.

4. In platform-scales, levers having their inner end portions overlapped and provided with pendent pivot-studs, a platform connection comprising an arm or lever and a shackle connected to said arm or lever and comprising upper and lower plates recessed in their top sides to receive the pendent pivot-studs of the platform-levers, and means for indepen-

ently adjusting the said plates, substantially as set forth.

In testimony whereof I affix my signature in presence of two witnesses.

AUGUST DOERING. [L. S.]
